UNITED STATES PATENT OFFICE

2,134,859

ELEVATOR

Charles B. Collins, San Anselmo, Calif.

Application December 16, 1936, Serial No. 116,157

3 Claims. (Cl. 121—46)

This invention relates to improvements in elevators and more particularly to pneumatic or fluid pressure elevators.

Among the objects is to provide an elevator comprising tubes telescoped within each other and adapted to raise safely and dependably both animate and inanimate objects.

Another object is to gradually retard each of the tubes as it nears the end of its operative movements.

Another object is to enable the upward movement of the elevator to be initiated smoothly.

Another object is to provide an elevator which is simple and relatively inexpensive in construction and permanently reliable in operation.

Other objects and advantages appear as this description progresses.

In this specification and the accompanying drawing, the invention is disclosed in its preferred form. It is to be understood, however, that it is not limited to this form because it may be embodied in other forms within the spirit of the invention as defined in the claims following the description.

25 In the one sheet of drawings:

Fig. 1 is a front elevation of an elevator constructed in accordance with this invention. The elevator is shown in extended position.

30 Fig. 2 is an enlarged vertical section of the upper portion of the elevator taken along the line II—II in Fig. 1.

Fig. 3 is a similar section taken along the line III—III in Fig. 1 showing the lower portion of the same in collapsed position.

35 Fig. 4 is a vertical section taken along the line IV—IV in Fig. 3.

In detail the structure illustrated in the drawing, referring more particularly to Fig. 3, comprises the base 1 which may be bolted to any 40 suitable support such as a vehicle. The base has the annular internally threaded flange 2 which has the lower end of the tube 3 screwed thereto.

A plurality of tubes 4, 5 of progressively smaller 45 diameter are telescoped within the outer tube 3. Two telescoped tubes are illustrated in the accompanying drawing. However, a larger number of tubes may be employed as desired, within the purview of the invention.

50 The innermost tube 5 has the bracket 5' fixed on, and sealing its upper end. A suitable goods platform may be mounted upon this bracket.

The lower ends of the tubes 3 and 4 are closed by the plugs 6, 7 which have the radial flanges 8, 9 slidably engaging the interiors of the tubes

3 and 4, respectively. The sealing cups 10, 11 are mounted beneath the plugs 6 and 7 by the rings 12, 13 and the screws 14, 15. The lips of these cups operatively engage the adjacent interior surfaces of the tubes 3, 4 to prevent the upward escape of air therewith between the telescoped tubes.

The annular guides 16 and 17 are threaded in the upper ends of the tubes 3, 4 and are slidably engaged by the telescoped tubes 4, 5. The sealing cups 18, composed of flexible material such as leather, are fixed underneath the guides 16, 17 and engage the exterior surface of the tubes 4, 5. These cups prevent the upward escape of air past the guides 16, 17.

The flanges 8, 9 cooperate with the guides 16, 17 to confine the tubes 4, 5 to vertical movement and enable the structure to withstand lateral thrusts.

The rings 19, 20 are welded or otherwise secured to the sides of the tubes 4, 5 slightly above the flanges 8, 9 and have the leather sealing cups 21, 22 fixed thereto. The lips of these cups operatively engage the outer tubes 3, 4 and prevent the escape of air downward past the rings 25 19, 20. Thus there is a quantity of air impounded between the cups 18—22, see Fig. 2, on the upward movement of the elevator. This air serves as a retarding cushion as will be later described.

The hollow valve stem 23 has its lower end screwed into the center of the base 1. The plugs 6, 7 have the openings 24, 25 therethrough to pass the stem 23. The openings 24, 25 are a close sliding fit over the stem 23 so as to minimize the 35 flow of air therewith. The stem has the tapered head 26 with the orifice 27 therethrough.

The base 1 has the passages 28, 29 therein which communicate with the interior of the stem 23. The passage 28 is closed by the stop cock 40 30 which discharges into the atmosphere. The valve 31 is screwed into the end of the passage 29 and has the hose 32 connected thereto which leads to a suitable source of compressed air. The passage has the restriction 33 therein.

The hollow valve 34 is a sliding fit within the stem 23. It has the orifice 35 through its upper end and the smaller ports 36 and 37 through its side. The holes 38 and 39 are adapted to register with the ports 36 and 37 and are located immediately below the plugs 6 and 7 respectively when the hoist is in collapsed position as in Fig. 3. The setscrew 40 in the stem 23 engages the groove 41 to hold the valve 34 against rotation. The spring 42 expands between the head 26 of 55

the stem and the top of the valve 34. It urges the valve into depressed position as in Fig. 3 with the ports 36, 37 out of registry with the holes 38, 39.

5 The springs 43 and 44 are interposed between the base 1 and the cap 6 and between the cap 6 and the cap 7, respectively. These springs yieldingly limit the downward movement of the tubes 4 and 5. The upward movement of the tubes 4 and 5 is limited by the pins 45 and 46. These pins are fixed in the rings 19 and 20 and project upwardly through holes provided in the sealing cup structure 21 and 22 and are arranged to abut the annular guides 16 and 17 at the end of the operative upward movement of the tubes 4 and 5.

In one use, the invention operates substantially as follows: Assuming the elevator to be in collapsed condition, a quantity of freight is loaded on to the goods platform (not shown) mounted on the bracket 5'. The goods on the platform may then be raised to the desired level, such as the top of the stack of goods and unloaded.

Opening the valve 31 permits compressed air from the hose 32 to flow into the passage 29 at a rate predetermined by the restriction 33. The compressed air passes from the passage 29, through the valve 34, the orifice 35, the orifice 27, into the interior of the tube 5. The orifice 35 is slightly smaller than the orifice 27. The air thus flows from the stem 23 through the orifice 27 as fast as it can be supplied by the smaller orifice 35. The back pressure due to the orifice 27 will thus be negligible. A pressure differential may thus be built up on opposite sides of the restriction at 35. The valve 34 is raised by this pressure differential and by friction incidental to the velocity of the air flowing therethrough until its movement is checked by the screw 40 engaging the end of the groove 41. The ports 36, 37 then register with the holes 38, 39 permitting compressed air to flow underneath the plugs 6 and 7. The relatively small space beneath these plugs results in a high air pressure being quickly built up. The tubes 4 and 5 then simultaneously commence moving upward with respect to each other and with respect to the outer tube 3.

When the plugs 6 and 7 pass beyond the end of the stem 23, compressed air flowing through the orifice 27 and the ports 36 and 37 maintains equal pressures in the tube 4 and the tube 5. The two tubes thus continue to rise at equal rates.

There is a quantity of air impounded between the rings 19, 20 and the guides 16, 17 outside the tubes 4 and 5 respectively. As the tubes 4 and 5 ascend in unison this entrapped air is compressed and exerts a progressively increasing retarding force against the resting tubes. The hoist rises at moderate speed until it nears the end of its movement. The pressure of the entrapped air rises and brings the tubes to a gradual stop obviating shock as the air slowly leaks past the cups 18 and 21, 22.

The ends of the pins 45, 56 come into engagement with the guides 16 and 17 positively limiting the travel of the tubes. The structure is arranged so that the flanges 8 and 9 come to rest a short distance below the guides 16 and 17 so as to render the hoist laterally stable when raised. The valve 31 is closed when the movement of the tubes ceases.

The platform is lowered by opening the valve 30. The compressed air within the tubes then flows downward through the orifice 27, into the stem 23, and through the passage 28 and out 75 the valve 30 into the atmosphere. The decrease

in pressure within the tubes 4, 5 allows them to descend under their own weight and that of any goods on the platform above. As the rings 19, 20 move away from the guides 16, 17, air flows from the atmosphere past the cups 18 into the space between the rings and guides.

The rate of descent will vary with the weight of the goods on the platform. To prevent too rapid descent when the platform is heavily loaded, the valve 30 can be only partially opened. This restricts the discharge of air and retards the descent of the tubes 4 and 5.

Near the end of the downward travel of the tubes, the plugs 6 and 7 slide over the stem 23. The valve 24 is urged by the expansion of the spring 42 into depressed position as in Fig. 3 with the ports 36, 37 out of registry with the ports 38, 39. The air underneath the plugs 6, 7 is thus trapped and can escape only by slow leakage through the slight clearance provided between the stem 23 and the openings 24 and 25. The final portion of the downward movement of the hoist is thus retarded and cushioned by the necessary compression of the air beneath the plugs 6, 7. The tubes 4, 5 finally come to rest 25 when the plugs 6, 7 engage the springs 43, 44.

Having thus described the invention, what is claimed and desired to be secured by Letters Patent is:

1. An elevator comprising a base; a tube fixed on said base; a plurality of telescoped tubes telescoping within said fixed tube and having plugs in their lower ends with openings therethrough; a valve stem fixed on said base and projecting upwardly therefrom; means for admitting and withdrawing fluid pressure from said tubes through said valve stem to raise and lower said tubes relative to each other; said valve stem being adapted to close the openings in said plugs when said tubes approach the terminus of their downward movement; said valve stem having ports through its side to admit fluid pressure beneath each of said plugs to initiate the upward movement of said tubes; and means for closing said ports during the downward movement of said tubes.

2. An elevator comprising a base; a tube fixed on said base; a plurality of telescoped tubes telescoping within said fixed tube and having plugs in their lower ends with openings therethrough; a valve stem fixed on said base and projecting upwardly therefrom and having an orifice in the top thereof; means for admitting and withdrawing fluid pressure from said tubes through said orifice in said valve stem to raise and lower said tubes relative to each other; said valve stem being adapted to enter and substantially close the openings in said plugs when said tubes approach the terminus of their downward movement; said valve stem having lateral ports therein to admit fluid pressure beneath each of said plugs to initiate the upward movement of said tubes, a hollow valve within said valve stem adapted normally to close said lateral ports in said stem and arranged to open said ports when said valve is displaced by the passage of fluid pressure through said stem and orifice therein into said telescoping tube.

3. An elevator comprising a base; a tube fixed on said base; a plurality of telescoped tubes telescoping within said fixed tube and having plugs in their lower ends with openings therethrough; a valve stem fixed on said base in registry with said openings and projecting upwardly therefrom, and having an orifice in the top thereof;

means for admitting and withdrawing fluid pressure from said tubes through said orifice in said valve stem to raise and lower said tubes relative to each other; said valve stem being adapted to 5 enter and substantially close the openings in said plugs when said tubes approach the terminus of their downward movement; said valve stem having ports through its side to admit fluid pressure beneath each of said plugs to initiate the upward 10 movement of said tubes; a hollow valve within said stem having ports therethrough adapted to

register with the ports in the side of said stem; resilient means urging said valve downwardly into a position with its ports out of registry with the ports in the side of said stem; said valve being adapted to be raised against the tension of 5 said spring by the passage of fluid through said stem into said tubes so as to bring the ports therein into registry with the ports in the side of said stem.
